UNITED STATES PATENT OFFICE

BEECH R. MANSFIELD, OF SEMINOLE, OKLAHOMA

JOCKEY STICK

Application filed November 26, 1927. Serial No. 235,929.

This invention aims to provide novel means whereby the line clamp in a drilling rig may be prevented from turning on the temper screw, the construction being such that the 5 temper screw can, nevertheless, continue its right-line vertical reciprocation, as the walking beam which carries the temper screw is operated.

It is within the province of the disclosure 10 to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes 20 herein disclosed, may be made within the scope of what is claimed, without departing from the spirit of the invention.

In the drawings:—

Figure 1 shows in elevation, a portion of 25 a drilling rig whereunto the device forming the subject matter of this application has been connected;

Figure 2 is a horizontal section in which the device, for the most part, appears in top 30 plan;

Figure 3 is a side elevation of the device per se; and

Figure 4 is a perspective view showing the 35 radius arm.

The numeral 1 marks the walking beam of a drilling or pumping rig, the walking beam being fulcrumed intermediate its ends, as indicated at 2. The numeral 3 designates a support, sometimes known as the "headache 40 post" because it is provided in order to prevent an operator from being injured by falling parts. The temper screw 4 is pivoted to the walking beam 1 and is threaded into a hanger 5 including one or more links 6 carrying the clamp 7 which engages and holds 45 the line 8.

A pivot element 9, such as a bolt, is mounted in the post 3 transversely thereof and passes through a sleeve 10 secured to one end 50 of a radius arm 11, the pivot element 9 and

the sleeve 10 constituting means for mounting the radius arm 11 for swinging movement. The radius arm 11 is provided at its upper end with bifurcations 22 having a plurality of openings 12, receiving for adjustment, a pivot element 14, which may be a bolt. The numeral 15 denotes a link made up of parts 16 and 17 disposed at an obtuse angle to each other, the part 16 being much longer than the part 17. One end of the part 16 of the link 15 extends between the bifurcations 22 of the radius arm 11 and is mounted pivotally on the bolt 14, the part 16 having a plurality of openings 36 that provide for an adjustable mounting of the link on 60 the pivot element 14. The outer end of the part 17 is received between the inner ends of jaws 18, and by means of a bolt 19, or otherwise, the inner ends of the jaws 18 are connected to the outer end of the part 17 of the link 15. The part 6 of the hanger 5 is received between the jaws 18, and the jaws 18 may be provided with seats 20 for one side portion of the link 6. The jaws 18 are connected by a pair of tightening bolts 21 75 located on opposite sides of the seat 20, and immediately adjacent thereto. The jaws 18 are connected adjacent to their outer ends by tightening bolts 23 which may be arranged on opposite sides of the outer arm of 80 the link 6.

In practical operation, the radius arm 11 and the link 15 can swing in a vertical plane, with the pivot elements 14 and 9 as centers in order that the temper screw 4 may have 85 straight-line vertical movement as the walking beam 1 swings up and down. However, owing to the fact that the member 6 is engaged between jaws 18 on the link 15, the clamp 7 and the hanger 5 cannot turn on the 90 lower end of the temper screw 4.

What is claimed is:—

1. In a device of the class described, a radius arm provided at one end with bifurcations, and supplied at its opposite end with a laterally off-set sleeve, a pivot element mounted in the sleeve, a link, means for connecting one end of the link adjustably between the bifurcations of the radius arm, and means mounted on the opposite end of the 100

link for holding a line clamp against rotation.

2. The combination with the line clamp and the support of a drilling rig, of a radius arm disposed approximately parallel to the line which the clamp holds, means for mounting the radius arm at its lower end for swinging movement on the support toward and away from the clamp, a link disposed approximately at right angles to the line which the clamp holds, means for connecting the outer end of the link to the clamp, and an adjustable pivotal connection between the inner end of the link and the upper end of the radius arm.

In testimony that I claim the foregoing as my own, I have hereto affixed my signature.

BEECH R. MANSFIELD.
